UNITED STATES PATENT OFFICE.

HORACE E. MORRILL, OF DAYTON, OHIO, ASSIGNOR TO THE DAYTON
MALLEABLE IRON COMPANY, OF DAYTON, OHIO, A CORPORATION
OF OHIO.

WRENCH.

No. 851,428.

Specification of Letters Patent.

Patented April 23, 1907.

Application filed April 20, 1906. Serial No. 312,769.

To all whom it may concern:

Be it known that I, HORACE E. MORRILL, a citizen of the United States, residing at Dayton, in the county of Montgomery and

5 State of Ohio, have invented certain new and useful Improvements in Wrenches, of which the following is a specification.

The invention relates particularly to wrenches for buggies and wagons in which 10 special provision is necessary for enabling the wrench to grasp the axle nut in the hub of the wheel, and has for its objects; to provide a wrench of this type which will hold the nut without being in danger of turning over 15 when the wrench is laid down; to provide a wrench in which the extended nut socket will be stiffened and reinforced; and finally, to provide an effective and serviceable wrench of inexpensive construction. The invention 20 is illustrated in the accompanying drawing, in which—

Figure 1 is a side view of the wrench;

Figure 2 is a longitudinal section through the wrench on the line (2) (2) of Figure 3;

25 Figure 3 is a plan view of the wrench, and Figure 4 is a plan view of a modified form of the wrench.

In buggy wrenches an extended socket is necessary in order that the nut in the recess 30 of the hub may be engaged, and it has heretofore been common to provide the extension by giving the handle a crook, but this construction has been found objectionable for the reason that after the nut is removed and 35 the wrench laid down it would turn sideways, thereby allowing the nut to fall out and become covered with dirt, and furthermore the nut cannot be placed in stable equilibrium upon a small support such as the carriage 40 step which is usually utilized for retaining the wrench after the nut has been removed. The objection to this wrench has been in a measure overcome by providing a heavy body portion and mounting the nut socket 45 on an arm projecting at right angles to the body of the wrench, but this type has also been found objectionable, as it is difficult to cast such a shape and is weak in the projecting arm, and when constructed by building 50 up of wrought material is too expensive for ordinary use. My invention has been directed to obviating the above objections, and to providing a wrench which can be cast and made comparatively light, and yet which will

when laid down remain in stable equilibrium 55 where placed, and which can be supported securely on a small surface such as a carriage step.

As shown in Figures 1, 2 and 3, 5 is the handle of the wrench carrying at its end the 60 broad extended portion 6, from which projects the sides of the nut socket 7. The handle may be of any preferred type, but is ordinarily made in the shape indicated,—that is, slightly cylindrical for the purpose of giving 65 strength for the least material, and for affording a good support for the hand. The portion 6 is of considerable breadth and is flat on the bottom to afford a stable supporting base when the wrench is laid upon its 70 back. It will be noted that the base 6 and the underside of the handle are in line. The socket 7, as is shown, projects from and is stiffened and supported by the base portion 6. It will be observed that when the wrench 75 is placed upon its back, carrying the nut, it will be in exceedingly stable equilibrium because of the broad base 6, and that, because of the large amount of metal at the end of the wrench which carries the nut socket, compared with the amount of metal in the handle; that it may be laid upon the support which extends only a short distance back on the handle without danger of the handle overbalancing the socket end. It will also be 80 seen that the wrench is one which may be very easily and inexpensively produced, and that for the amount of metal used a maximum strength is secured.

I have shown in Figure 4 a modified form 90 of wrench. In this form it will be seen that the flat portion 6 is provided with a plurality of open sided sockets, and that the central portion of the part 6 is cored out to form an additional socket 8. These additional nut 95 engaging portions considerably increase the range of the wrench and add to its efficiency without disturbing the function of the wrench, as heretofore described. It will be seen that in this form, as in the form shown in Figures 1, 100 2 and 3, the base portion serves to strengthen and support the portion 7, thereby permitting of a lighter construction of such nut socket than would otherwise be possible.

Having thus described my invention and 105 illustrated its use, what I claim as new and desire to secure by Letters Patent, is the following:

1. In combination in a wrench, a flat broad base, having a central nut socket and a plurality of open sided nut sockets surrounding the central socket, a handle lying substantially in the same plane as the base, and an upstanding nut socket having its walls located inside the open sided nut sockets and supported directly on such base, whereby the projecting walls of such upstanding socket and the base mutually support and brace each other.
2. In combination in a wrench, a flat broad base portion having a plurality of open sided nut sockets arranged around the edge thereof,

a handle lying in substantially the same 15 plane as the base, and an upstanding nut socket having its walls supported directly on the said base inside the opensided nut sockets, whereby the projecting walls of such upstanding socket and the base mutually support and 20 brace each other.

In testimony whereof I have hereunto signed my name in the presence of the two subscribed witnesses.

HORACE E. MORRILL.
